DESIGN FOR A PIN OR SIMILAR ARTICLE

Benjamin Margone, Bronx, and Herman Shweder,
Brooklyn, N. Y.

Application January 26, 1942, Serial No. 105,438

Term of patent 3½ years

To all whom it may concern:

Be it known that we, Benjamin Margone and Herman Shweder, both citizens of the United States and residents, respectively, of the Bronx, New York, in the county of Bronx and State of New York, and Brooklyn, New York, in the county of Kings and State of New York, have invented a new, original, and ornamental Design for a Pin or Similar Article, of which the following is a specification, reference being had to the accompanying drawing, forming a part thereof, and of which Figure 1 is a view in front elevation of a pin or similar article showing our new design; Fig. 2 is a top plan view thereof, and Figs. 3 and 4 are sectional views thereof taken on lines 3—3 and 4—4 of Fig. 1, respectively.

We claim:

The ornamental design for a pin or similar article, substantially as shown.

BENJAMIN MARGONE.
HERMAN SHWEDEER.
